UNITED STATES PATENT OFFICE.

WILLIAM HOLSTEIN, OF CHICAGO, ILLINOIS.

SASH LOCK.

Application filed February 27, 1922. Serial No. 539,372.

To all whom it may concern:

Be it known that I, WILLIAM HOLSTEIN, a citizen of the United States, residing at Chicago, in the county of Cook and State 5 of Illinois, have invented certain new and useful Improvements in Sash Locks, of which the following is a specification.

This invention relates to a lock for sliding sashes, the principal purposes in view being simplicity in manufacture and assembly; also ease and dependability in operation.

An exemplification of this invention in its preferred form is illustrated in the accompanying drawing wherein—

15 Figure 1 shows in transverse section the adjacent rails of two window sashes on one of which is mounted the present lock;

Fig. 2 is a perspective of the lock *per se*; and

20 Fig. 3 shows the blank from which the block holder is formed.

The present lock is adaptable to sliding doors or sashes such, for instance, as is shown fragmentarily in Fig. 1 where the 25 upper rail A of an inner sash lies adjacent the lower rail B of an outer sash. The lock is mounted upon the rail A of the inner sash so as to present one of its elements in juxtaposition to a vertical rail C of the outer sash for the purpose of engaging therewith when desired.

The device which constitutes my invention comprises three principal elements, *viz.*, the bracket D in which is pivotally mounted a holder E for a friction block F. The bracket D may be formed from sheet metal which is suitably shaped and bent to provide a base plate 5 having one or more apertures 6 therein through each of which is inserted a nail or screw 7 for securing the device to the rail A of the inner sash. Extending upwardly from opposite sides of the base are two supporting arms 8 of any suitable configuration, each having near its upper edge an opening adapted to receive the ends 9 of a pivot pin.

Associated with a bracket of the general kind described, is a holder E preferably formed from a blank such as is shown in 50 Fig. 3. When folded into shape, the holder comprises a bottom 10 from each side of which extends upwardly a retaining wall 11,

the rear ends 12 of which are bent around toward each other in overlapping relation so as to provide a back of double thickness, 55 as best shown in Fig. 2.

Secured within the holder just described is a friction block F preferably made of rubber hardened to a desired degree. This block is rectangular in shape and of a size to rest 60 upon the holder bottom 10 and be confined between its two retaining walls 11. When so positioned with one of its edges adjacent the holder back, as shown in Fig. 2, the block may be secured therein as through the medium of a screw 15 having an eye 16 at its outer end and a flange 17 adapted to abut the outer rear wall 12 when in final position. The shank of the screw, which is threaded in the ordinary manner, is adapted to enter 70 into the rubber block so as to engage therewith, thereby providing a means of securing the block within the holder. The block may be formed with an opening 20 relatively close to one of its corners (*or, if desired, 75 with a similar opening in each of its corners*), adapted to register with other openings 21 formed in the retaining walls of the holder. Through the holes thus formed in the holder, as well as the openings in the bracket supporting arms 8, is inserted a pin whose ends 9 may be upset or otherwise formed to maintain the holder in permanently pivotal relation therewith. This pin traverses also the friction block, passing through 80 one of its corner openings 20 and acts, independently of the screw eye, to secure the block within the holder.

It is preferred that the four edges of the block, each of which is of a substantial area, 90 shall be corrugated, serrated, or otherwise roughened, as indicated by the numeral 23, so that when the device is positioned relatively close to an outer sash, as indicated in Fig. 1, one of these roughened edges will 95 engage with the sash rail C with such friction as to effectively resist any sliding movement thereof relative to the inner sash. The normal locking position of the device is about as indicated by the full lines in Fig. 1. If 100 an effort be made to forcibly slide either sash relative to the other, the block, through its frictional engagement with the outer sash, will resist this movement, yielding per-

haps to a slight extent. Its maximum yield is about as indicated by the dotted lines where it will be noted that the outer lower corner 24 of the block has come into contact with the base plate 5, or sash rail A, the material of the block being compressed to a considerable extent during this movement. No further pivotal movement can take place, however, and consequently neither 5 sash can be opened relative to the other. It is to be noted that in this position of maximum pivotal movement, the block has turned slightly less than 45° , in which position its body is compressed to the maximum that is 10 possible. This is of importance because, unless the pivotal movement of the block be arrested at about this place, its continued rotation would carry its engaging face past the point of maximum radius with a resulting diminution of pressure upon the sash rail C; in such circumstances further perseverance of an intruder would probably enable him to force the lock.

Normally the friction block is turned back 25 to an inoperative position as shown by the other set of dotted lines in Fig. 1, where it will be noted the eye 16 of the screw is rested upon the bracket base, or upon the sash rail A, to stop this reverse movement. These 30 operations of the block may perhaps be facilitated, by tying to the screw eye a cord (not shown) which will facilitate manipulations thereof. In swinging the block forwardly into engaging position with the sash 35 rail C, it is important to note that the lower outer corner 24 comes in contact therewith only slightly in advance of the entire engaging face due to the fact that the pivotal mounting of the block and holder therefor is situated very close to one corner thereof.

It is to be observed that the parts which comprise my invention are few in number, and may be readily assembled so as to insure 45 operation with certainty. Modifications of this construction within certain limits are, of course, possible without departing from the spirit of my invention, and are to be deemed as within the purview thereof, if 50 embraced within the language of the claims following.

I claim:

1. A sash lock of the kind described comprising, in combination, a bracket having two supporting arms in spaced relation, each 55 provided with an opening which registers with the other, a holder formed of sheet metal which is bent to provide a bottom from which extend two retaining side walls, each of the latter having portions bent toward the other in overlapping relation to 60 provide a back, and a rubber block of generally rectangular shape adapted to be received within the holder with one edge resting upon the bottom, another edge against 65 the back, and two of its sides confined in

part by the retaining walls thereof, and means for securing the block within the holder comprising a pin passing through the body thereof and through two openings formed in the retaining walls of the holder, 70 the pin extremities passing also through the openings in the bracket supporting arms to provide a pivotal mounting for the holder therewithin, substantially as described.

2. A sash lock of the kind described comprising, in combination, a bracket, a holder, a yieldable friction block supported within the holder, and means passing through the bracket, holder, and block adapted to provide a pivotal mounting for the holder and 80 to retain the block therewithin, substantially as described.

3. A sash lock of the kind described comprising, in combination, a bracket, a holder, a yieldable rectangular friction block supported within the holder with two of the block sides and edges engaged by the holder, a pivotal connection between the bracket and holder passing through the body of the block near one corner thereof, the bottom 90 edge of the block being situated above the bracket base a distance which permits its downward rotation thereupon of less than 45 degrees from the horizontal, substantially as described.

4. A sash lock of the kind described comprising, in combination, a friction block of general rectangular shape having its edges suitably roughened, a holder for the block consisting of a piece of sheet metal bent to 100 provide a bottom which engages one block edge, two sides which lie adjacent portions of opposite sides of the block, and a back formed by rearward extensions from each holder side, each lapping the other, the back 105 engaging another side of the block, means for securing the block within the holder comprising a screw passing through the double back of the holder to engage with the block and having a portion of itself engaging the outer holder side, and means providing a pivotal connection between the holder and a support therefor, substantially as described.

5. A sash lock of the kind described comprising, in combination a holder formed of sheet metal having portions thereof each lapped to provide a double back, a friction block within the holder, means providing a pivotal mounting for the holder within a 110 bracket such that the block may swing downwardly from the horizontal a distance of less than 45° , and means passing through the double back of the holder engaging with the block for retaining the same therewithin, said means having a portion extending rearwardly of the back to provide a stop for the holder when rotated in a 115 reverse direction, substantially as described.

6. A sash lock of the kind described com-

prising, in combination, a holder, a yieldable rectangular friction block supported within the holder, a support, means extending through the block, holder, and support block being so related to the support as to have a downward swinging movement thereupon of less than 45 degrees from the horizontal, substantially as described. 10

5 adapted to provide a pivotal connection for the holder relative to the support and to retain the block fixedly within the holder, the

WILLIAM HOLSTEIN.
